M. WAGNER.
VALVES FOR WATER JACKETED EXPLOSION ENGINES.
APPLICATION FILED JUNE 6, 1913.

Patented Aug. 18, 1914.

UNITED STATES PATENT OFFICE.

MICHAEL WAGNER, OF PITTSBURGH, PENNSYLVANIA, ASSIGNOR OF ONE-FOURTH TO
SAMUEL SILBERSTEIN, OF PITTSBURGH, PENNSYLVANIA.

VALVES FOR WATER-JACKETED EXPLOSION-ENGINES.

1,107,635.

Specification of Letters Patent.

Patented Aug. 18, 1914.

Application filed June 6, 1913. Serial No. 772,066.

To all whom it may concern:

Be it known that I, MICHAEL WAGNER, a citizen of the United States, residing at Pittsburgh, in the county of Allegheny and State of Pennsylvania, have invented certain new and useful Improvements in Valves for Water-Jacketed Explosion-Engines, of which the following is a specification.

The invention relates to explosion engines, and particularly to valve mechanism for controlling the inflow and drainage of the water jacket. The invention has for its primary objects; the provision of an improved safety arrangement of valves for insuring the opening of the drainage outlet from the water jacket and closing of the inlet thereto when the fuel supply inlet is closed, and vice versa; and the provision of means of the character specified of very compact construction, and one in which improved means are provided for throttling the fluids passing through the inlet pipes. One embodiment of the invention is illustrated in the accompanying drawing, where-

Figure 1 is a side elevation of an engine with my improved valve applied thereto, Fig. 2 is a transverse section through the valve mechanism, on the line II-II of Fig. 3, Fig. 3 is a plan view of the valve, with one of the three similar parts thereof in section to show the interior construction, and Fig. 4 is a side elevation of the valve.

It frequently happens in cold weather that the water jackets of gas engines are burst through failure to drain the jacket after the engine has stopped at night, and failure to cut off the supply of water to the jacket. My invention is designed to overcome this difficulty, by the provision of an arrangement whereby the drainage pipe from the water jacket is opened and the supply pipe closed, when the gas supply is cut off. Conversely the arrangement provides for the closure of the drainage pipe and the opening of the supply pipe to the jacket, when the gas or fuel supply pipe is opened. The arrangement not only guards against the bursting of the water jacket through failure to drain the jacket after the engine is stopped at night, but also

guards against starting the engine without supplying water to the water jacket.

Referring first to the general arrangement of parts indicated in Fig. 1, 1 is the water jacket around the cylinder of the gas engine illustrated; 2 is the water supply pipe for the jacket, connected to a water main; 3 is the drain pipe for the water jacket, such drain pipe leading into the sewer 4; 5 is the gas or fuel supply pipe leading to the carbureter 6; 7 is the water outlet pipe from the jacket, leading to the sewer; and 8 is the casing of the valve mechanism for controlling the supply of fluid through the pipes 2, 3, and 5.

The construction of the valve mechanism in the casing 8 will be understood by reference to Figs. 2, 3, and 4. Mounted in the casing are three transversely extending rotary valves 9, 10, and 11 (Fig. 2). These valves are tapered in the customary way in order to make a tight fit, and are provided with the transverse openings 12, 13, and 14 adapted to register with the openings 15, 16, and 17 extending through the valve casing, it being understood that the portions of the pipes 2, 3, and 5 lying on opposite sides of the valve casing 8 are screw threaded into the sockets on opposite sides of the casing as indicated in Fig. 2, so that the passages 15, 16, and 17 constitute in effect portions of the pipes 5, 3, and 2, respectively.

The outer ends of the valves 9, 10, and 11 are squared as indicated in Fig. 4, and carry the handles 18, 19, and 20 connected by the bar 21. The handle 19 is extended as indicated at 22, to provide an operating means so that the three valves may be moved simultaneously. When the member 22 is in the position indicated in Figs. 1 and 4, the valves occupy the position indicated in Fig. 2, at which time the drain pipe 3 is closed and the gas and water inlet pipes 95 are open, this being the position when the engine is working. It will be seen that the member 22 must be moved to this position in order to admit fuel to the engine, and that this movement insures the opening of the water inlet pipe to the jacket, and the closing of the drain, so that all danger of

running the engine with an empty jacket is eliminated. When the handle 22 is swung 90° to the right the drainage valve 10 is opened, and the gas and water inlet pipes 5 and 2 respectively closed, such movement occurring when the engine is shut down. The closing off of the gas therefore necessarily involves the opening of the drain pipe and the closing of the water supply pipe 10 to the jacket, so that the jacket will immediately drain, and all danger of bursting due to freezing with a full jacket is avoided.

The inner ends of the valves 9, 10, and 11 are threaded as indicated at 23, such threaded portions carrying the washers 24 and nuts 25. One side of the threaded portion 23 is cut away to provide a flat surface 26, and the interior of the washer 24 is formed so as to fit the flat portion 26 so that the washer turns with the valve. This eliminates the tendency of the nut 25 to unscrew as would be the case if the washer did not turn with the valve. This is a well known mechanical expedient for which no claim is made.

Inside each of the valves 9, 10, and 11 is a rotary throttling plug. These plugs are all similar in construction and bear the reference numerals 27, 28, and 29 (Figs. 2 and 3). As indicated in Fig. 3, the central portion of the plug 27 is partially cut away so that the plug only partially blocks the passage 12. It will be seen that more and more of the passage 12 may be blocked by the plug 27, by rotating it about its axis. This plug therefore serves as a convenient means for throttling the flow of fluid through the valve casing. The outer ends of the plugs 27, 28, and 29 are squared and carry the relatively short handles 30, 31 and 32 (Fig. 4). The flow of fluid through each of the valve parts may thus be readily throttled to suit conditions, and the necessity of other throttling devices in the pipes 2, 3, and 5 is thus eliminated.

The inner ends of the throttling plugs 27, 28, and 29 are provided with screw threaded portions 33 carrying washers 34 and nuts 35. The portions 33 have a flat portion at one side so that the washers 34 which fit the flat portions turn with the stems 33 and nuts 35, and any tendency to unscrew the nuts is eliminated. The plugs 27, 28, and 29 are tapered in order to make a tight fit with the valves through which they extend.

It will be understood that the particular embodiment of the invention illustrated and described constitutes only one of a number of forms in which the invention may be practised. The invention is readily applicable to systems other than the one shown for providing a circulation of water through the water jacket, the system illustrated being somewhat wasteful because the water is directed back into the sewer instead of be-

ing circulated, but such system is sufficient for the purposes of illustration. A large variety of valve structures might be substituted for the one shown, the only requirement being that the common operating means control all three passages, so that when the drain is closed the gas and water supply pipes will be open, and vice versa. The use of the three independent valves is not necessary, although convenient in that it permits independent adjustment and independent accessibility to each valve for the purpose of repairs. It is also obvious that where separate valves are used as illustrated, a large number of different mechanical equivalents might be employed for securing simultaneous movement of the valves, depending upon the character of the valves and their degree of proximity.

What I claim is:

1. The combination with an explosion motor having a fuel supply inlet, and a water jacket provided with a water inlet and a drainage outlet, of valve mechanism having passages forming part of the said fuel inlet, water inlet and drainage outlet respectively, and controlling means for the said passages having a common actuating member so that all said controlling means are actuated during the movement of the actuating member, the said controlling means being positioned so that the drainage passage in the said valve mechanism is open when the fuel and water inlet passages in the valve mechanism are closed and so that the said drainage passage is closed when the said fuel inlet and water inlet passages are open.

2. The combination with an explosion motor having a fuel supply inlet, and a water jacket provided with a water inlet and a drainage outlet, of valve mechanism having passages forming part of the said fuel inlet, water inlet and drainage outlet respectively, controlling means for the said passages having a common actuating means so that said controlling means are actuated simultaneously, and throttling means carried by a part of said controlling means for adjusting the flow past such controlling means when in full open position, the said controlling means being so positioned that the drainage passage in the said valve mechanism is open when the fuel and water inlet passages in the valve mechanism are closed and so that the said drainage passage is closed when the said fuel inlet and water inlet passages are open.

3. The combination with an explosion motor having a fuel supply inlet and a water jacket provided with a water inlet and a drainage outlet, of rotary plug valves in the said inlets and outlet, connections whereby the valves are rotated together, and a rotatably adjustable throttling plug in one

of the rotary valves for controlling the flow of fluid through its passage, the valves being so arranged that when the valve in the drainage outlet is in open position the other

5 two valves are in closed position, and when the valve in the drainage outlet is closed, the other two valves are in open position.

In testimony whereof I have hereunto signed my name in the presence of the two subscribed witnesses.

MICHAEL WAGNER.
